(57) **CLAIM**

The ornamental design for a shelf fence component, as shown and described.

DESCRIPTION

FIG. 1 is a perspective view of a shelf fence component, showing my new design;

FIG. 2 is a back perspective view of the shelf fence component shown in FIG. 1;

FIG. 3 is a right side elevation view of the shelf fence component shown in FIG. 1;

FIG. 4 is a left side elevation view of the shelf fence component shown in FIG. 1;

FIG. 5 is a front elevation view of the shelf fence component shown in FIG. 1;

FIG. 6 is a back elevation view of the shelf fence component shown in FIG. 1;

FIG. 7 is a top plan view of the shelf fence component shown in FIG. 1;

FIG. 8 is a bottom plan view of the shelf fence component shown in FIG. 1; and,

FIG. 9 is a perspective view showing an exemplary shelf fence including a plurality of the shelf fence components shown in FIGS. 1 through 8 attached to an exemplary wire shelf.

The details shown in broken lines are for illustrative purposes only and form no part of the claimed design. In FIGS. 1 through 6, the separation and bracket are used to indicate indeterminate length, as the shelf fence component can be shorter or longer than shown in the figures.
